MARIUS LATOUR, OF PARIS, FRANCE, ASSIGNOR TO LATOUR CORPORATION, OF JERSEY CITY, NEW JERSEY, A CORPORATION OF DELAWARE.

NEGATIVE IMPEDANCE DEVICE.

Application filed November 20, 1923, Serial No. 675,833, and in France December 5, 1922.

This invention relates to improvements in arrangements for producing negative impedance, and has for its purpose the production of negative impedance which may be 5 interposed in a telephone line in order to counterbalance the impedance of the line and reduce the attenuation, but it will be understood that this invention is not limited to the use just indicated.

10 Various specific features of the invention will appear from the detailed description and appended claims.

My invention is illustrated in the accompanying drawing, in which—

15 Fig. 1 shows one form of my invention as embodied in a resistance-coupled amplifier;

Fig. 2 shows an arrangement according to my invention utilizing transformer coupling; and

20 Figs. 3 and 4 show arrangements of apparatus adapted to be inserted in a telephone line to reduce attenuation and prevent distortion.

In Fig. 1 there are shown two three-electrode vacuum tubes 1 and 2, each having a plate, a filament and a grid with circuits arranged to constitute a two-stage resistance-coupled amplifier. The plate circuit of 25 vacuum tube 1 is energized by the combined

voltages of batteries 3 and 5 through resistance 12. The voltage of battery 5 is such that it normally compensates for the resistance drop of the plate voltage in resistance 12 in such a manner that the voltage between 30 points 10 and 11 is normally equal to zero.

35 In the same way, the plate circuit of vacuum tube 2 is energized by the sum of the two voltages of the batteries 4 and 6 through resistance 15, the voltage of battery 6 being such that the resultant voltage between terminals 13 and 14 is normally zero. An impedance 9 having a value z is shunted between the grid and filament of vacuum tube 1 between the terminals 7 and 8.

40 From Fig. 1 it will be noted that there is a circuit including the various terminals 7, 8, 11, 14 and 13 and if we consider that a current flows in this circuit through the impedance 9 which has a value z , it will be 45 understood that the passage of current develops a voltage zi between the grid and filament of vacuum tube 1 and this voltage amplified successively by the two vacuum tubes 1 and 2 results, in accordance with the 50 usual characteristic of vacuum tubes, as a

negative ohmic drop between the points 14 and 13 of the resistance 15. It, therefore, results that for a suitable value of impedance 9 having a resistance, an inductive reactance, and capacitance, there is obtained between terminals 7 and 13 a negative impedance depending on the characteristics of the circuits. 60

In order to obtain a negative impedance of a sign exactly opposite to that of the impedance 9, which is connected in shunt to the grid and filament of the first vacuum tube 1, it is necessary to place in series with the impedance 9 a certain resistance 16 which, transformed into a negative resistance by the operation of the amplifying system, serves to counterbalance the effect of the positive resistance connected in the plate circuit of the second vacuum tube 2. The resistance 16 is substantially equal to 75 the resistance 15. 70

According to this invention, we may employ instead of direct coupling by resistance, coupling by transformers 17 and 18 as shown in Fig. 2 in which the same reference characters indicate the same parts as in Fig. 1. In this case an even number of tubes is no longer necessary. It is sufficient to take a convenient sense of circulation of the windings of the transformers interposed in 80 the work circuit and the number of tubes may be anything. If it is supposed that we have to do with a perfect type of transformer (magnetizing current zero, capacity of windings zero, leakage zero, losses zero), 85 the operation will be that shown in Fig. 1. In practice it should be arranged that transformers 17 and 18 approach the perfect type of transformer with the order of magnitude of the frequencies considered. The 90 magnetizing current may be compensated by a capacity in shunt. These transformers may be without iron in the case of very high frequencies. The input transformer, on the other hand, may be arranged with a ratio 95 of transformation sufficiently low so as not to cause in the grid filament circuit a resultant effect capable of disturbing the desired operation. The resistance 15 may be variable; it may be represented by the winding 100 connected to the plate and represented even by the losses in the iron of the transformer.

Fig. 3 shows an arrangement in which the real impedance z is a cable or artificial line equivalent to a real cable or real line in a 110

manner to obtain a negative impedance capable of being imposed in a telephone transmission circuit to reduce the attenuation. The resistance 16 is separated into two elements for symmetry.

In Fig. 4 the cable or artificial line corresponds to a cable or artificial line of inverse constants, as compared with Fig. 3, (capacities in series and inductances in shunt), in such a manner that the negative impedance obtained may permit not only the reduction of the attenuation, but prevent distortion. In a general way, the real impedance 9 may be constituted by all elements appropriately selected, inductances, capacities and resistances combined in any manner to represent a suitable artificial line.

In order to satisfy symmetry, we may arrange two amplifier systems for a single line. In the first system the grid circuit may be on the north side and the plate circuit on the south side; while in the second system the grid circuit will be on the south side and the plate circuit on the north after the manner of the well known one-way repeater. The real impedance 9 may also be, for example, the modulation circuit of a magnetic amplifier or of a frequency multiplier, the excitation circuit of a high frequency alternator and in a general way any circuit presenting a reactance which is a function of the frequency. The distortion suffered by telephonic current in traversing such a circuit

may then be prevented by providing on the plate side a negative impedance of a valve equivalent to that shunted about the grid side in such a way that the whole represents only a residual impedance corresponding to a pure ohmic resistance.

Having described my invention, what I claim is:

1. In apparatus for producing a negative impedance, a vacuum tube amplifier comprising an anode, a cathode and a control electrode, an impedance connected in circuit between said cathode and said control electrode, a transformer having its windings inserted in the control circuit of said amplifier, and a second transformer inserted in the output circuit of said amplifier.

2. In an arrangement for producing negative impedance, the combination of a vacuum tube amplifier having an anode, a cathode and a control electrode, an input circuit comprising an impedance having a resistance associated therewith, an output circuit comprising a resistance, a transformer having its primary shunting said impedance, and its secondary connected in the control circuit of said amplifier, and a second transformer having its primary winding in the anode-cathode circuit of said amplifier and its secondary winding shunting the resistance in said output circuit.

MARIUS LATOUR.
